UNITED STATES PATENT OFFICE.

SEVERN D. SPRONG AND WALTER E. MCCOY, OF NEW YORK, N. Y.

MEANS FOR PREVENTING CURRENT LEAKAGE IN ELECTRIC CABLES.

1,165,140.

Specification of Letters Patent. Patented Dec. 21, 1915.

Application filed February 12, 1915. Serial No. 7,849.

To all whom it may concern:

Be it known that we, SEVERN D. SPRONG and WALTER E. MCCOY, citizens of the United States, residing at New York, in the county of New York and State of New York, have invented a certain new and useful improvement in Means for Preventing Current Leakage in Electric Cables, of which the following is a specification.

10 For convenience of manufacture and handling, electric cables are made in short lengths joined together usually after being placed in position. Much difficulty has been experienced in preventing leakage at the 15 joints between the several line conductors which form the cable and which are usually embedded in an insulating compound which fills the protective inclosing metal sheath. The ordinary way of making these joints is, 20 after the metallic conductors are exposed and united at their extremities, to wrap said conductors with layers of insulating tape, with intervening coatings of varnish or the like, until a desired thickness of envelop is obtained, or sometimes by covering the 25 metallic joint with a tube of insulating material. In using the first method it often happens that owing to the location of the joint it is impossible to get such access to 30 the cable as that the insulating tape can be evenly wound thereon or that the varnish can be applied so as to insure its percolation into the space between the windings and layers. Hence the insulation at the 35 joint becomes less in dielectric strength than the insulation existing elsewhere and applied during the process of manufacture. So also it is impossible to apply such a wrapping without imprisoning air contained 40 in the interstices of the material and between the turns of the wrapping, and as the air always contains moisture, the latter diminishes the insulating properties of the covering. In the second method, where an 45 insulating tube is used, it is necessary to remove the insulation of the conductors for a length in excess of the length of the tube, since it is necessary in order to apply the tube to the joint to thread one of the conductors through the tube before the ends are 50 metallically united, and, furthermore, in order to accommodate a sufficient thickness of wrapping and varnish layers between the

tube and the conductor, it is necessary to make the tube of large diameter, and this in turn correspondingly increases the diameter of the lead sleeve which finally and hermetically seals the joint.

The principle of our invention is to construct the joint covering as that a dielectric strength of the insulation between the several conductors and between each conductor and the outer sheath—hence ground—will be greater than that hitherto existing. This we effect by means of inclosing mutilated tubes of material of high dielectric strength which are applied to the line conductors laterally or, in other words, without threading the conductors through them, and which are embedded in the insulating compound which fills the sheath. The relative arrangement of the tubes is such that a creeping current must find its way through the insulating filling within a tube to a gap in the tube wall, and thence through the insulating filling outside the tube to a similar gap in the wall of the next adjacent tube, and then through the filling in that tube before it can pass from one conductor to another.

In the accompanying drawings, Figure 1 is a longitudinal section of our cable joint on the line 1, 1 of Fig. 3. Fig. 2 is an elevation of the completed joint, a portion being broken away. Fig. 3 is a cross section on the line 3, 3 of Fig. 1. Fig. 4 is a similar cross section of a modification of our joint.

Similar numbers and letters of reference indicate like parts.

The cable here shown comprises three metallic conductors A, B, C, each having the usual insulating cover D, and all inclosed in a sheath E, usually of lead. The space within the sheath not occupied by said conductors is filled with an insulating compound F introduced in a plastic or fluid state and allowed to harden. We will explain the operation of forming and covering the joint with reference to one of said conductors, it being the same for all. The sheath is cut away and then the insulating filling compound, as shown at 3 and 4, so as to expose a sufficient length of the cover D, which in turn is cut away, as shown at 5, so as to expose the naked wires of the

conductor B, B. Upon the sheath E of one part of the cable is slid a tube G of fiber or other insulating material which is pushed back on said sheath, as shown in dotted lines, Fig. 1, so as to be well away from the joint. Upon the tube G is placed a section of lead sheathing H, and this is also slid back from the joint in the same way as is tube G. The ends of conductor B, B being cut off square and approximated face to face, are inserted in a short copper sleeve I, having openings through which molten tin or solder is run. Said tin binds the said approximated ends together and fills the annular space between said sleeve and said wires and also the openings in said sleeve. We then place upon the conductor a mutilated tube J of lenticular or elliptical cross section and made of fiber or other material of high dielectric strength. Said tube extends over the sleeve I and exposed ends of conductor B, B and may, if desired, reach to the shoulders formed by cutting away the insulating filling F at 3, 4. In the wall of the tube J is a gap K, through which the conductor passes when the tube is placed thereon. This gap is located at one end of the major axis of the elliptical figure formed by a cross section of the tube. The gap may be enlarged to permit the passage of the conductor by springing its edges apart. The conductor is, therefore, not threaded through the tube from end to end, but the tube is placed bodily upon the conductor after the joint between the meeting ends thereof is formed.

The ends of the other conductors of the cable are joined in the manner already described, and tubes L, M, similar to tube J, are applied thereto. The tubes J, L, M are to be so placed relatively to one another that their gaps, similar to K, are all turned in the same direction, as shown in Fig. 3. After the three tubes J, L, M have been put in place, we slide the tube G longitudinally until its ends lap over the cut off end portions of the insulating filling F, as shown in Fig. 1. We then slide the sheath section H in like manner, so as to cover the tube G, and so that its extremities will lap over the ends of the lead sheath E on the cable. We then bend inwardly the extremities of the tube section H until they meet sheath E, and between said extremities and said sheath we form with solder a wiped joint, as shown at N, Fig. 2. Openings are made in tube H by suitably cutting the wall thereof and bending back the same, as shown at O, Fig. 1. Through these openings is poured viscid or plastic insulating compound, which then fills all the open spaces within said sheath and there hardens.

In the modification shown in Fig. 4, curved plates P, Q, R, also of material of high dielectric strength, are placed between

the conductors A, B, C. The widths of these plates are such that their outer edges meet the inner periphery of tube G, so that they form partitions dividing the space within said tube into three compartments, each containing one conductor and its surrounding mutilated tube.

By the before described construction, we reduce any possible leakage of current between the conductors A, B, C to a minimum. The dielectric strength of tubes J, L, M is greater than that of the insulating filling F. Hence the current on one conductor, as C, Fig. 3, cannot find its way either through said filling directly to either of the other conductors, but must proceed over a path represented by the curved arrow R in Fig. 3, that is, from conductor C, through the gap in tube M, then through the insulating filling to the gap in tube L, and so to conductor A. The length of this path is obviously longer than the thickness of the insulating filling measured in a straight line from conductor C to conductor A. Hence the effect of the added tubes J, L, M is substantially largely to augment the resistance offered to the passage of the current from one conductor to the other without requiring any actual increase in distance between these conductors or enlargement of the cable diameter. So also the intervention of the tubes J, L, M between the cables A, B, C and the outer sheath along the line largely increases the resistance in the path of current proceeding from the conductors to said sheath and ground.

In the form shown in Fig. 4, the path of the leakage current is still further obstructed by the partitions P, Q, R.

We claim:

1. An electric cable, comprising an inclosing tube, a jointed line conductor therein, a filling of insulating material in said inclosing tube, and a tube of insulating material embedded in said filling and inclosing said joint; the said last-named tube being substantially elliptical in cross section and of material of greater dielectric strength than said filling and having a longitudinal gap in its wall located at one end of the major axis of said cross sectional ellipse.

2. An electric cable, comprising an inclosing tube, a plurality of jointed line conductors therein, a filling of insulating material in said inclosing tube, and tubes of insulating material embedded in said filling and respectively inclosing said conductors; each of said last-named tubes being substantially elliptical in cross section and of material of greater dielectric strength than said filling and having a longitudinal gap in its wall located at one end of the major axis of said cross sectional ellipse, and the said major axis lying each at an angle to a radius struck from the center of the circular cross

section of said inclosing tube, and the gap in each inner tube being approximated to the wall of the next adjacent inner tube.

3. An electric cable, comprising an inclosing tube, a plurality of longitudinal partitions of insulating material therein forming compartments, a jointed conductor disposed in each compartment, a filling of insulating material in said compartments, and in each 10 compartment a tube of insulating material embedded in said insulating filling and inclosing the conductor therein: each of said last-named tubes and said partitions being of material of greater dielectric strength 15 than said filling.

4. An electric cable, comprising an inclosing tube, longitudinal partitions of insulating material in said tube dividing the same into compartments, a plurality of jointed 20 conductors respectively disposed in said compartments, a filling of insulating material in said compartments, and tubes of

insulating material embedded in said filling and respectively inclosing said conductors: each of said last-named tubes and said partitions being of material of greater dielectric strength 25 than said filling and each of said inner tubes being substantially elliptical in cross section and having a longitudinal gap in its wall located at one end of the major 30 axis of said cross sectional ellipse, and the said major axes lying each at an angle to a radius struck from the center of the circular cross section of said inclosing tube, and the gap in each inner tube being approximated 35 to the wall of the next adjacent inner tube.

In testimony whereof we have affixed our signatures in presence of two witnesses.
